FILAMENT STORING AND TENSIONING DEVICE

Raymond O. Letsch, 329 Mulberry Ave., Waterloo, Iowa

Filed Jan. 26, 1959, Ser. No. 789,042

3 Claims. (Cl. 242—129.8)

The present invention relates to tensioning means for filaments, such as string, yarn, thread, wire and the like, and particularly, to an improved combination filament storing and tensioning device.

In drawing a filament from a source of supply, it is frequently desirable to apply back-tension to the filament to insure proper application of the filament and to mitigate over-supply of the same from the source and tangling of the filament between the source and the point of application. The degree of tension to be applied to the filament will, of course, vary from application to application, and from time to time in each application.

One object of the present invention is to provide improved tensioning means for filaments that is adjustable to apply to the filament a back-tension anywhere within the range of from substantially zero to the breaking strength of the filament.

Another object of the invention is to provide, in combination, a storage chamber for the filament and the tensioning means above described.

Yet another object of the invention is the provision of an improved tensioning device for simultaneously applying back-tension to a plurality of filaments.

A further and more specific object of the invention is the provision of an improved tensioning device comprising a pair of members relatively adjustable along a given axis, each of said members having a filament receiving aperture therein the axis of which generally parallels said given axis, the aperture in one member being eccentric to the aperture in the other member for causing a portion of a filament threaded through said apertures to be offset between the two members, the two members being movable toward one another for fixedly clamping the said portion of the filament therebetween and being movable away from one another for progressively relieving the clamping force of said members on the filament.

A still further object of the invention is the provision of an improved tensioning device as above defined wherein at least one member has a plurality of apertures therein which are spaced from one another and are all eccentric to the aperture in the other member, whereby the device may simultaneously apply back-tension to each of a plurality of filaments.

An additional object of the invention is to provide, in a preferred embodiment, a combined filament storing and tensioning device comprising a container for filament, said filament container having an end wall and a screw threaded portion circumscribing said wall, and a screw threaded cap adjustably mounted on said portion of said container and having an end wall opposed to the end wall of said container, one of said end walls having a filament receiving aperture therein axially of said screw threaded portion, and the other of said end walls having at least one filament receiving aperture eccentric to said screw threaded portion, whereby a filament passing from said container through said apertures is laterally offset in the space between said walls and said cap is adjustable on said con-

tainer for clamping the filament between said end walls and for imposing on the filament varying degrees of back-tension.

Other objects and advantages of the invention will become apparent in the following detailed description.

Now, in order to acquaint those skilled in the art with the manner of making and using the improved filament storing and tensioning means of my invention, I shall describe, in connection with the accompanying drawing, preferred embodiments of my invention and preferred manners of making and using the same.

In the drawing, wherein like reference numerals indicate like parts:

Figure 1 is a side elevation of a preferred embodiment of a device for storing and applying back-tension to a single filament;

Figure 2 is a fragmentary vertical section, on an enlarged scale, of the tensioning means embodied in the device of Figure 1, the view showing the cap of the device adjusted to apply a relatively slight back-tension to the filament;

Figure 3 is a fragmentary vertical section similar to Figure 2, but showing the cap adjusted to fixedly clamp the filament to the device; and

Figure 4 is a fragmentary vertical section similar to Figures 3 and 4 illustrating one embodiment of a device for storing and applying back-tension to a plurality of filaments.

Referring now to the drawing, and particularly to Figures 1 to 3, I have shown a preferred embodiment of my device as comprising a hollow cylindrical container 10 defining a filament storage chamber therein and including at one end a reduced cylindrical extension 12. The extension 12 defines a relatively thick end wall at the one end of the container, and is provided on its peripheral surface with a screw thread. This thread may be of any standard form and lead, and may be either a "fast" thread or a "slow" thread as desired for a particular application.

A cap member 22 is mounted on the stem 12 for adjustment axially thereof by means of a screw thread that is complementary to and meshes with the thread on the extension 12. The cap 22 is preferably formed to include a relatively thick end wall portion, and the end wall of the cap and the end wall of the container, as defined by the extension 12, are provided with apertures 24 and 14, respectively, which are laterally offset from and eccentric relative to one another. The axes of the two apertures are preferably parallel to one another and the axis of the container 10 and cap 22, and I prefer to dispose one of the apertures with its axis coincident with the axis of rotation of the cap. In the preferred embodiment of the device illustrated herein, I form the aperture 24 axially in the cap 22, and locate the aperture 14 eccentric thereto.

By virtue of the relative eccentricity of the two apertures, a filament 26 stored within the container 10 and threaded through the two apertures, will have a portion thereof laterally offset in the space between the end walls defined by the extension 12 and the cap 22. Upon threading of the cap 22 tightly onto the extension 12, this portion of the filament will become fixedly clamped between the two end walls, as is illustrated in Figure 3. By unthreading the cap 22, the filament is permitted progressively greater freedom of movement in its passage from the aperture 14 to the aperture 24, thereby progressively to relieve the back-tension applied to the filament. By way of example, I have illustrated in Figure 2 the cap 22 unthreaded by about half the length of its thread, in which condition a relatively slight degree of back-tension is applied to the filament as it is withdrawn from the aperture 24. By simple screw threaded adjustment of the cap 22, substantially any desired degree of back-tension

sion can be applied to the filament, depending upon the particular application of the filament.

In the preferred structure, the apertures 14 and 24 are of significantly greater diameter than the filament, so that the walls of the apertures will not, per se, impose significant back-tension on the filament, whereby the device may be adjusted to impose substantially no drag on the filament if that should be desired from time to time. Such relative sizing of the apertures also facilitates threading of the filament.

The filament is preferably associated with the device by first removing the cap 22 from the device, threading the filament 26 through the aperture 14 from the interior of the chamber defined by the container 10, then depositing the supply of filament, such as a ball, spool, coil or skein thereof, into the chamber, subsequently threading the filament through the aperture 24, and finally re-applying the cap 22 to the extension 12. As will be apparent, the size of the container relative to the size of the extension 12 and cap 22 is of no particular significance, the container being of such size as is desired for convenient reception therein of the supply reel or ball of the filament to which back-tension is to be applied.

To complete the device, I prefer to provide a screw threaded closure 16 for the end of the container 10 opposite the cap 22, i.e., the open end of the container. To facilitate convenient disposition of the combined storing and tensioning device, for example to accommodate hanging of the same on a supporting hook or the like, I prefer to provide the end closure 16 with a bail 18 that is pivotally mounted on the closure by means of a strap 20.

From the foregoing, it is apparent that the present invention provides a particularly economical and compact device for storing filaments and for applying back-tension to the filament according to the demands of the particular application. Adjustment of the device to vary the back-tension applied to the filament is very conveniently and accurately effected.

In addition, the device of the present invention is readily adapted to handle a plurality of filaments by the simple expedient of providing additional apertures in the end wall of at least one of the caps 22 and container 10, which additional apertures are spaced from the other aperture or apertures in the respective wall and are eccentric to or laterally offset from the aperture, or a respective aperture, in the other end wall. In a preferred embodiment of a device for handling, for example, two filaments, I prefer to provide a pair of apertures or passageways 14a and 14b in the end wall defined by the extension 12, which apertures or passageways are spaced from one another and are both eccentric to the axis of the aperture 24 and the cap 22, as is shown in Figure 4. With this structure, a first filament may be threaded through the passageways 14a and 24 and a second filament may be threaded through the passageways 14b and 24, whereby the two filaments may simultaneously be drawn from the container through a common outlet, the device of the invention applying substantially equal back-tension to both of the filaments. Modifications of this arrangement are, of course, to be expected from those skilled in the art.

While I have shown and described what I regard to be the preferred embodiments of my invention, it will be apparent that various changes, rearrangements and

modifications may be made therein without departing from the scope of the invention, as defined by the appended claims.

I claim:

5 1. A filament tensioning device comprising a pair of members having cooperating screw threads thereon for adjusting the two members relative to one another along a given axis, said members having opposed walls disposed transversely of said axis, each of said members having a 10 filament receiving aperture in the said wall thereof the axis of which generally parallels said given axis, the aperture in one member being generally coincident with said given axis and the aperture in the other member being eccentric to said axis for causing a portion of a filament threaded through said apertures to be offset between the 15 two members, the two members being threadably movable toward one another for fixedly clamping the said portion of the filament between the opposed walls thereof and being threadably movable away from one another for progressively relieving the clamping force of said members on the filament and for imposing a predetermined back-tension on the filament.

2. A combined filament storing and tensioning device comprising a container for filament, said filament container having an end wall, a cap having an end wall opposed to the end wall of said container, and means adjustably mounting said cap on said container for accommodating movement of said end walls toward and away from one another, each of said end walls having a filament receiving passageway therethrough, the passageway in one member being eccentric to the passageway in the other member for causing a portion of a filament threaded through said passageways to be offset between the two end walls, said cap being adjustably movable on said container toward the end wall thereof for fixedly clamping the said portion of the filament between said end walls and being adjustably movable on said container away from the end wall thereof for progressively relieving the clamping force on the filament and for imposing on the filament a predetermined degree of back-tension.

3. A combined filament storing and tensioning device comprising a container for filament, said filament container having an end wall and a screw threaded portion circumscribing said wall, and a screw threaded cap adjustably mounted on said portion of said container and having an end wall opposed to the end wall of said container, one of said end walls having a filament receiving aperture therein axially of said screw threaded portion, the other of said end walls having at least one filament receiving aperture therein eccentric to said screw threaded portion, whereby a filament passing from said container through said apertures is laterally offset in the space between said walls and said cap is adjustable on said container for clamping the filament between said end walls and for imposing on the filament varying degrees of back-tension.
